UNITED STATES PATENT OFFICE.

MARK B. KERR, OF ROSEBANK, NEW YORK, ASSIGNOR TO WESTERN ELECTRIC COMPANY, INCORPORATED, OF NEW YORK, N. Y., A CORPORATION OF NEW YORK.

TELEGRAPH SYSTEM.

Application filed February 1, 1922. Serial No. 533,179.

To all whom it may concern:

Be it known that I, MARK B. KERR, a citizen of the United States, residing at Rosebank, Staten Island, in the county of Richmond, State of New York, have invented certain new and useful Improvements in Telegraph Systems, of which the following is a full, clear, concise, and exact description.

10 This invention relates to telegraph systems.

An object of the invention is to provide a system whereby a plurality of telegraph messages originating at separate stations 15 may be transmitted over a plurality of branch lines or extension circuits to main or central stations where synchronous multiplex apparatus is located for automatically and simultaneously transferring the code combinations of signaling impulses to a line connecting the central stations.

Another object is the provision of means associated with the synchronous multiplex apparatus for providing a complete overlap 25 between the selections received from the extension circuits or branch lines and those transmitted by the synchronous multiplex apparatus to the line connecting the central stations.

30 The invention provides synchronous multiplex and start-stop apparatus at the central stations with means associated therewith, such as a series of condensers and a plurality of groups of relays for providing a complete overlap between the selections so that irrespective of what the phase relation between the start-stop and the synchronous multiplex apparatus is, the selections coming in on the start-stop will be directly transmitted to the multiplex apparatus providing 35 that the speed of the start-stop is exactly equal or slightly less than the multiplex apparatus.

35 The invention is illustrated in the accompanying drawings which represent one embodiment of the invention, and when arranged so that Fig. 1 is to the left of Fig. 2, a complete system is shown diagrammatically.

50 The invention, in general, comprises a branch office A, which is connected with a main or central office B by an extension circuit or branch line 6. A central or main station C connected with the main station B by a line conductor 7 equipped with duplex

apparatus and a distant branch office D, which, like the branch office A, is connected with the associated central station C by an extension circuit 8.

At the branch office A there are located 60 transmitting and receiving equipments E and F, respectively, being shown diagrammatically. The extension circuit 6 may be a pair of line conductors or a single line conductor equipped with duplex apparatus, as 65 illustrated in the drawings. Both of the central stations B and C are provided with receiving distributors G and H of the start-stop type, serving to receive the code combinations of message impulses from the respective substations or branch offices and transferring them to the multiplex synchronous distributors I and L, also located at the offices B and C, respectively, through the instrumentalities of a plurality of condensers 70 in combination with a plurality of groups of relays. Also located at these central offices are multiplex synchronous distributors K and M, each of which serves to receive the signaling impulses from the line conductor 75 connecting these two stations and transferring the same to the start-stop distributors N and R, respectively. Branch office D, like branch office A, is provided with a transmitting distributor P and a receiving distributor 80 Q, which serve their respective purposes. For the sake of simplifying the drawing, the apparatus common to one channel has been shown in detail, while that individual to the other channel has been shown schematically.

85 The transmitting equipment E comprises an intermittently operable rotary distributor 10, having a brush arm 11 which carries a pair of brushes 12 and 13 which, in turn, are 90 arranged to make contact with rings 14, 15, 16, and 17. The outer ring 17 is divided into a plurality of segments 18, 19, 20, 21, 22, and 23, which are connected with the respective contacts of a transmitter shown diagrammatically at 24. In order that the brush arm 11 will be stopped and released once per revolution, a release magnet 27 is provided which is under the control of a start relay 28, which is controlled by a common contact on the transmitter 24.

100 The transmitter 24 consists of a plurality of movable contacts 30, 31, 32, 33, and 34, which are connected to the respective segments forming the outer ring 17 of the dis-

tributor 10. Also in the transmitter 24 is a common contact 35, which, as previously stated, controls the energization of the start relay 28. Although the transmitter 24 has been shown diagrammatically as a keyboard transmitter, any well-known type of transmitter may be substituted therefor, which will provide equally good results.

At the central office B there is shown 10 a receiving distributor G of the start-stop type and a synchronously operated distributor I, which has its continuous ring 95 connected to the apex of the ratio arms, which include the receiving relay 99, forming a part of the duplex equipment connected with the line conductor 7. The line relay 99 responds only to incoming impulses and is non-responsive to outgoing impulses. Upon the operation of the multiplex distributor I, this relay will not respond to impulses which may be transferred thereto from the start-stop distributor G.

The start-stop distributor G comprises an 25 outer ring 44 and an inner ring 40. Forming a part of the outer ring is a plurality of segments 47, 48, 49, 50, 51, and 52, each of which corresponds to respective ones of the segments on the transmitting distributor 30 10. By the proper orientation of these segments and inasmuch as they are smaller than the transmitting segments of the transmitting distributor 10, the central portion of the signal impulses transmitted over 35 the extension circuit 6 to the line relay 37 will be picked up from each segment of the sending face at the branch office A. The distributor G also comprises a brush arm 41 carrying a brush 42 which is held against 40 rotation by a release latch 43 under the control of release magnet 39.

Interposed between the start-stop distributor G and the multiplex or synchronously operated distributor I is a set of condensers in combination with a pair of groups of storing relays operable in accordance with the signals transmitted and controlled by a series of transfer relays under the control of both the start-stop distributor G and the multiplex distributor I. The set of condensers and the two groups of relays, serve to provide a complete overlap between the selections received from the start-stop distributor G and those transmitted out over the line 7 by the multiplex distributor I, irrespective of what the phase relation is between the brush arm of the start-stop distributor G and the brush arm of the multiplex distributor I, providing, of course, that the speed of the brush arm of the start-stop distributor is exactly equal or slightly less than the speed of the brush arm of the multiplex distributor I. The condensers 56, 57, 58, 59, and 60 are connected directly to the receiving segments

forming the outer ring 44 of the distributor G, and will be charged in accordance with the operation of relay 38. The first set of storing relays comprises relays 70, 71, 72, 73, and 74, which are under the control of 70 the condensers 56 to 60, inclusive, the energizing circuits of which are completed through the armatures of transfer relay 61 which, as is more clearly described hereinafter, is controlled through the segments 43 75 and 52 of the distributor G. The second set of storing relays comprise the relays 76, 77, 78, 79, and 80, which are under the control of the first set of relays and are also locked up upon their energization. 80 Thus, after a set of impulses has been transmitted from the distributor G to the condensers 56 to 60, the transfer relay 61 is energized for establishing a discharge circuit for said condensers through the left-hand windings of the first set of storing relays 70 to 74 which will be energized depending upon which ones of the condensers are charged. These relays will also be locked up through their own contacts and 90 right-hand windings, and after their initial energization, are maintained energized independent of the condensers 56 to 60. After the impulses stored in the condensers have been cleared out the next succeeding series 95 of message impulses may be set up on the condensers 56 to 60, inclusive. After the first set of storing relays 70 to 74 are energized, they establish, through their contacts, 100 energizing circuits for the corresponding ones of the storing relays of the second set, which, like the first set, are locked up and maintained in such position until released by a relay under the control of the multiplex distributor I. It is through the contacts of the second set of storing relays 105 that the polarity of the impulses corresponding to the various characters is varied.

In order that the impulses will be transferred from the respective parts of the circuit so that no mutilation of signals will result, such transfer is under the joint control of the start-stop distributor G and the Synchronous multiplex distributor I as will be more clearly described hereinafter. 110

The apparatus just described constitutes the equipment located at the central or main station B, which serves to transmit impulses from the branch office A to the line conductor 7 and thence to the central office 120 C from which the message impulses are transmitted to the distant branch office D.

The apparatus at the central office C which receives the signals transmitted from the transmitting apparatus located at the 125 central office B comprises a multiplex distributor M and a distributor of the start-stop type R. The multiplex distributor M comprises, among other parts a continuous ring 113 and an outer ring which is divided 130

into a plurality of segments 107, 108, 109, 111 and 112. Like the distributor I a continuously revolving brush arm 102 carrying brushes 103 and 104 is also provided. Connected to the smaller segments forming a part of the outer ring are the windings of a set of storing relays 115, 118, 121, 124 and 127 which serve in combination with the other two sets of storing relays 114, 117, 121, 123, 126 and 116, 119, 122, 125 and 128 to provide a complete overlap between the selections transmitted from the multiplex distributor M and those transmitted over the extension circuit 8 by the start-stop distributor R.

The start-stop distributor R comprises an outer ring divided into a plurality of smaller segments 132, 133, 134, 135, 136 and 137. The first five of these segments are connected to the right-hand armatures of the storing relays 115, 118, 121, 124 and 127 which, upon their energization, are locked whereby the armatures thereof remain in the position set until due to a subsequent selection they are released for transmitting an effect opposite to that when they were energized. For bridging the outer ring of the distributor R, with the inner ring 138 the distributor has a brush 130 carried by a brush arm 129 which is normally held against rotation by a latch under the control of a release magnet 131. The release magnet 131 is controlled through contacts on the relays 114, 117, 120, 123 and 126 so that upon the energization of any one of these relays an energizing circuit for release magnet 131 is established for causing the release of the brush arm 129.

The receiving equipment Q at the branch office D comprises a receiving printer diagrammatically shown at 155 which comprises the usual selecting magnets 156, 157, 158, 159 and 160 and the printing magnet 168. The respective magnets have their windings connected to the segments 161, 162, 163, 164 and 165 forming a part of the outer ring of the receiving distributor 144. The distributor 144 like the distributor G has a brush arm 147 carrying a brush 148 which is arranged to bridge the segments forming a part of the outer ring with the segments 154, 166 and 152 for controlling the energization of the respective ones of the selecting magnets depending upon the energization of relay 151 which, in turn is controlled by the line relay 146 connected to the extension circuit 8.

Inasmuch as the apparatus associated with the other channel of the system is identical with the equipment just described, further description thereof is considered unnecessary here. However, the rectangles designated by the characters S and T represent the equipment intermediate the distributors G and I, and M and R respectively, which,

as previously described, are shown diagrammatically for the sake of clarifying the drawings.

The operation of the equipment just described is as follows: Assume for the sake of clearness that the branch office A desires to communicate with the branch office D in which case the transmitter 24 will be operated to set up a particular combination depending upon the message desired to be transmitted. Let it also be assumed that it is desired to transmit a character in which the contacts 30, 32 and 34 of the transmitter 24 are actuated to close their respective contacts. As previously described, upon the operation of the transmitter 24 contact 35 will be closed for causing the energization of start relay 28, the energizing circuit of which extends from battery, through the left-hand winding thereof, contact 35, segment 15, brush 13 and segment 14 of the transmitting distributor 10 to ground. The start relay 28 is thereupon energized and is locked up over a circuit under the control of brush 13. Upon the energization of the start relay 28, an energizing circuit is established for the release magnet 27 which in operating withdraws the release latch under its control from engagement with the brush arm 11 which is thereupon free to rotate whereupon the brush 12 consecutively completes circuits extending from the segments 18, 19, 20, 21 and 22, and the contacts of the transmitter 24 which have been operated through the winding of the pole changing relay 29. The pole changing relay 29 is energized upon the passage of the brush 12 over a segment to which one of the closed contacts of the transmitter 24 is connected for applying to the line 6 an impulse of a polarity corresponding to that normally applied thereto. However, the instant the brush 12 passes off of segment 23, an open circuit condition is established whereby the pole changing relay 29 reverses the position of its armature and connects the positive source of current with the apex of the ratio arms in which the receiving relay 36 is connected, but which does not respond to outgoing impulses. The receiving relay 37 located at the central office B does however, respond to such change in polarity and reverses the position of its armature whereby the energizing circuit of the relay 38 is broken, consequently, an energizing circuit for the release magnet 39 of the distributor G is established. The release magnet 39 being energized, the brush arm 41 is thereby released for rotation owing to the withdrawal of the release latch 43. Contact 30 of the transmitter 24 being closed an energizing circuit for the pole changing relay 29 is established upon the passage of the brush 12 over the segment 18 of the transmitting distributor 10, thus connecting the

negative pole of the battery with the line conductor 6 and consequently causing the reversal of the armature of the receiving relay 37 to the position shown in the drawing, which, in turn, causes the energization of the relay 38. The closure of the front contact of relay 38 establishes, upon the passage of the brush 42 over the segment 47, a charging circuit for the condenser 56 whereupon this condenser is charged. The contact 31 of the transmitter 24 being open, the pole changing relay 29 is caused to reverse the position of its armature upon the passage of the brush 12 over the segment 19 to which contact 31 of the transmitter is connected. Similarly, the receiving relay 27 at office B reverses the position of its armature and consequently causes the deenergization of relay 38. Thus, upon the passage of the brush 42 over segment 48 of the distributor G the condenser 57 will not be charged. Contact 32 and 34 being closed, conditions similar to those described in connection with contact 30 will be established for causing the condensers 58 and 60 to be charged in accordance with the energization of relay 38 upon the passage of the brush 42 over the segments to which these condensers are connected. Condenser 59 will however, not be charged owing to contact 33 of the transmitter being open, so that an open circuit condition is established upon the passage of the brush 42 over the segment individually thereto. Just prior to the completion of the cycle of rotation of the brush arm 41 of the distributor G an energizing circuit is established for relay 63 extending from battery through the left-hand winding of this relay, segment 52, brush 42 and the segment 46 to ground. Relay 63 is thereupon energized and locked up over a circuit extending from battery through the left-hand armature and contact thereof, right-hand winding and left-hand armature and normal contact of relay 64 to ground. Relay 63 in closing its right-hand contact establishes an energizing circuit for relay 62 which is of the slow to release type. The energizing circuit extends from the left-hand armature and normal contact of relay 65, winding of relay 62, right-hand armature and alternate contact of relay 63 and the normal contact and left-hand armature of relay 66 to ground. Relay 62 in closing its left-hand alternate contact establishes an energizing circuit for relay 64 whereupon the holding circuit of the relay 63 is broken thereby causing the deenergization of this relay. Upon the closure of the right-hand alternate contact of relay 62, an energizing circuit is established for the transfer relay 61 which controls a plurality of armatures to which the condensers 56 to 60 are connected for transferring the impulses stored on the condensers to the first set of storing relays 70, 71, 72 and 74. The condensers 56, 58 and 60 being charged in the manner previously described, relays 70, 72 and 74 of the first set of storing relays will be energized due to the establishment of a discharge circuit for these condensers upon the closure of the contacts under the control of the transfer relay 61. Relays 70, 72 and 74, upon closing their right-hand contacts, establish a locking circuit therefor extending from battery through the right-hand contact, armature and winding thereof and the right-hand armature and contact of relay 66 to ground. The condensers 57 and 59 not having been charged for the particular selection chosen remain discharged. Upon the opening of the left-hand contact of relay 63 the energizing circuit for the slow release relay 62 is open, which, in deenergizing, causes the deenergization of relay 64 which conditions an energizing circuit for the transfer relay 65 under the control of the multiplex distributor I. Upon the passage of the brush 88 over segment 97 of the multiplex distributor I an energizing circuit is established for relay 75 extending from battery, ring 98, brush 88, segment 97, winding of relay 75 and the right-hand armature and contact of relay 66 to ground. Relay 75 in closing its right-hand contact, establishes a locking circuit for itself while upon the closure of its left-hand contact an energizing circuit is established for relay 65 which extends from battery left-hand armature and normal contact of relay 62, right-hand armature and normal contact of relay 64, winding of relay 65 and the alternate contact and armature of relay 75 to ground. Relay 65 in energizing closes at its right-hand contact an energizing circuit for relays 76, 78 and 80 corresponding to the relays 70, 72 and 74 of the first set of storing relays which have been energized due to the discharge of the condensers 56, 58 and 60. The initial energizing circuit for these relays extends from battery through the winding thereof, left-hand armature and contact of the storing relays 70, 72 and 74 of the right-hand armature and contact of relay 65 to ground. Relays 76, 78 and 80 upon closing their lower contacts establishes a locking circuit therefor extending from battery through the winding of each of these relays, lower contact and armature thereof and the normal contact and armature of clear out relay 81 to ground. Relays 76, 78 and 80 thereupon remain energized until relay 81 is energized which, in turn, is under the control of the multiplex distributor I. Relay 65 in attracting its left-hand armature first, removes the battery connection to the slow to release magnet 62 thereby preventing the energization of this relay should, in the meantime, the relay 63 be energized.

- due to the bridging of the segments 52 and 46 of the distributor G by the brush 42, and secondly, establishes an energizing circuit for relay 66, which, as previously described, 5 controls the locking circuit of the first set of storing relays 70 to 74 so that any of these relays which happen to be energized at this time will be released for receiving the next succeeding set of impulses which 10 may have previously been stored on the condensers 56 to 60 and, of course, subsequent to the transfer of the previous charge to the relays forming the first set of storing relays.
- Upon the passage of the brush 89 of the 15 multiplex distributor I over the respective ones of the segments to which these relays are connected, a polarity of battery depending upon the energization of the storing relays 76 to 80 will be applied to the apex 20 of the ratio arms to which receiving relay 99 is connected and thence over the line conductor 7 to the central station C. Upon the passage of the brush 89 over segment 94 to which the armature of storing relay 76 is 25 connected, an impulse of positive polarity will be transmitted to the central station C which passes through the windings of the receiving relay 101 for causing the reversal of its armature. The negative pole of the 30 battery associated with the contacts of this relay is thereupon connected with ring 113 of the distributor M so that upon the passage of the brush 104 over the segment to which the storing relay 115 is connected this 35 relay will be energized over a circuit extending from battery, upper contact and armature of receiving relay 101, ring 113, brush 104, segment 107, right-hand armature and normal contact of relay 114, winding of relay 115 to ground. Relay 115 in closing its left-hand contact establishes an energizing circuit for itself extending from battery through the left-hand armature and contact of relay 116, winding of relay 114, left-hand 45 armature and contact and the winding of relay 115 to ground. Relay 114 being energized upon the establishment of the circuit just traced, opens upon the attraction of its armature the initial energizing circuit of relay 115 and closes at its right-hand alternate contact an energizing circuit for relay 116 which, as will be more clearly described hereinafter, is not energized until the reception of a subsequent selection of a polarity 50 opposite to the previous selection which caused the energization of relay 115. It is thus seen that the relay 115 will remain in the position set until the reception of a subsequent selecting unit differing in polarity 55 from the one which previously caused the energization of this relay. As the brush arm 87 continues to rotate, conditions depending upon the position of the armatures of the storing relay 76 to 80 inclusive, will 60 be set up for causing the corresponding position of the armature of receiving relay 101 at the central office C. Thus upon the passage of the brush 104 over the segments to which the storing relays 118, 121, 124 and 127 are normally connected, these relays 70 will be energized depending upon the energization of the storing relays of the second set located at the central office B. For the particular selection chosen, storing relays 121 and 127 will be energized over circuits 75 similar to that traced in connection with storing relay 115. The energized ones of these storing relays will also be locked up through contacts in a manner similar to that described in connection with the storing relay 115. Upon the passage of the brush 104 over the segment to which the storing relays 118 and 124 are connected these relays will not be energized owing to the position of the armature of relay 101. However, had these 80 relays been previously energized, an energizing circuit would be established for the relays 119 and 125 of the second set of storing relays, the circuit of which extends from battery, winding of these relays, right-hand 85 alternate contact and armature of relay 117, segment 108, brush 104, ring 113, armature and lower contact of relay 101 to ground. 90
- Following the passage of the brush 89 over segment 90 of the multiplex distributor I, the brush 88 engages segment 96, whereupon an energizing circuit is established for relay 81 which extends from battery through ring 98, brush 88, segment 96 and the winding of relay 81 to ground. Upon the energization of cut-out relay 81 the locking circuit for the relays 76, 78 and 80 is broken thereby restoring these relays to the position 95 shown in the drawings.
- Should the brush 88 of the multiplex distributor I pass over segment 97 prior to the passage of the brush 42 over segments 46 and 52 of the distributor G, the energization of relay 62 will be prevented due to the energization of relay 65 in the manner previously 100 described. Thus, upon the continued rotation of the brush arm 87 no mutilation or piling up of the signals will be caused owing to the energization of relay 65 and nothing 105 will occur except the transmission of a blank 110 signal over the line conductor 7, which will have no effect on the printing mechanism at the branch office D.
- Following the passage of the brush 104 of the multiplex distributor M over segment 112, brush 103 bridges segment 105 with ring 106, whereupon an energizing circuit 115 is established for the release magnet 131 of the start-stop distributor R. This circuit extends from battery through the winding of the release magnet 131, conductor 139, segment 105, brush 103 and ring 106 to ground. Release magnet 131 upon being energized withdraws its release latch from engagement with the brush arm 129 thereby 120
- 125
- 130

permitting the rotation thereof. The brush 130 carried by the brush arm 129 consecutively connects the segments 132, 133, 134, 135 and 136, which are connected with respective armatures of the storing relays 115, 118, 121, 124 and 127 in circuit with the winding of the pole changing relay 142. Prior to the engagement of the brush 130 with the segment 132 and upon the passage 10 of this brush off of segment 137, pole changing relay 142 is deenergized thereby impressing on the extension circuit 8 an impulse of a positive polarity which, upon being received at the branch office D causes the reversal of the armature of the receiving relay 146. Relay 146 in reversing the position of its armature causes the deenergization of relay 151 which, in turn, closes through its back contact an energizing circuit for the release magnet 150 of the distributor 144, thus releasing the brush arm 147 for rotation.

Upon the passage of the brush 130 over segment 132 and owing to the fact that the 25 storing relay 115 is energized an energizing circuit is established for the pole changing relay 142 extending from battery to the ring 138, brush 130, segment 132 of the distributor R, right-hand armature and contact of storing relay 115 and the winding of the pole changing relay 142 to ground. The closure of such a circuit causes the energization of the pole changing relay 142, which impresses on the extension circuit 8 an impulse of a negative polarity for causing the reversal of the position of the armature of the receiving relay 146 to the position shown in the drawing, consequently causing the energization of relay 151. Relay 151 being 40 now energized upon the passage of the brush 148 over segment 161, selecting magnet 153 connected to this segment will be energized over a circuit extending from battery through the winding of this magnet, segment 161, brush 148; ring 154 and the alternate contact and armature of relay 151 to ground. The movement of the selecting bar under the control of this magnet will be effected at this time.

50 The brush 130 in passing over segment 133 and inasmuch as storing relay 118 is not energized, causes the pole changing relay 142 to reverse the position of its armature and impresses on the extension circuit 8 an impulse of a positive polarity. Similarly, 55 upon the passage of the brush 148 over segment 162 to which the selecting magnet 157 is connected, an open circuit condition is established owing to the fact that the receiving relay 146 has reversed the position of its armature and, in turn, caused the deenergization of relay 151. Conditions similar to those just described for selecting magnet 156 will be established upon the passage of 60 the brush 148 over segments 163 and 165

respectively, for causing the energization of the corresponding selecting magnets 158 and 160 of the receiving printer 155. However, since the storing relay 124 is not energized for this selection, no effect will be produced 70 on the selecting magnet 159 upon the passage of the brush 148 over segment 164 to which this selecting magnet is connected.

Following the passage of the brush 148 off of segment 165 and the passage thereof 75 over segment 166 and 167 a circuit is completed extending from battery through the winding of printing magnet 168, segment 167, brush 148 and segment 166 to ground. Thus, the signals transmitted from the 80 branch office A will be recorded on the receiving printer 155 at the branch office D over one channel of the line conductor 7 equipped for duplex operation.

Although the invention has been illustrated in connection with a system where-in code combinations of message impulses originating at a branch office are transferred to a main or central office at which synchronous printing telegraph apparatus is located 90 and thence over a conductor equipped for duplex operation to a second central or main station having equipment similar to that just referred to from which it is transferred over an extension circuit to a distant office, it is, of course, obvious that the invention may be readily applied to other types of systems without departing from the spirit and scope of the present invention.

What is claimed is:

1. In a signaling system, receiving and transmitting distributor mechanisms, signal storing means intermediate said mechanisms for providing a complete overlap between the selection received by the receiving distributor mechanism and those transmitted by the transmitting distributor mechanism comprising electrostatic means and a plurality of sets of storing relays, and means controlled by the receiving distributor mechanism for transferring the effects of said electrostatic means to said relays. 105
2. In a signaling system, receiving and transmitting distributor mechanisms, signal storing means intermediate said mechanisms for providing a complete overlap between the selection received by the receiving distributor mechanism and those transmitted by the transmitting mechanism comprising electrostatic means and a plurality of sets of storing relays, and means controlled by the transmitting distributor mechanism for preventing the transfer of the effects of said electrostatic means until after a predetermined time. 110
3. In a telegraph system, a plurality of stations interconnected by a line conductor, duplex equipment located at each of said stations, synchronous multiplex apparatus associated with said duplex equipment, an 115 120 125 130

extension circuit, intermittently operable apparatus located at said stations and connected to said extension circuit, storing means intermediate said multiplex and said intermittently operable apparatus comprising a series of electrostatic devices, and a plurality of sets of storing relays for providing a complete overlap between the selection received by the intermittently operable apparatus and those transmitted by the synchronous multiplex apparatus.

4. In combination a line conductor equipped for duplex operation connecting two main stations, synchronous multiplex apparatus located at said main stations and connected to said line conductor, an extension circuit extending from a branch office to said main office, intermittently operable distributors located at said main station and connected to said extension circuit, and storing means intermediate said multiplex apparatus and said intermittently operable distributors comprising a series of condensers corresponding in number to the number of code units employed and a plurality of sets of storing relays for providing a complete overlap between the selections received by the intermittently operable distributor and those transmitted by the synchronous multiplex apparatus, and means controlled by the intermittently operable distributor for trans-

ferring the effects of current impulses stored on said condensers due to the operation of said distributor to said storing relays.

5. In combination a line conductor 35 equipped for duplex operation extending between two central stations, synchronous multiplex apparatus associated with said line and located at said central stations, an extension circuit, a start-stop distributor located at said central stations and connected to said extension circuit, and storing means intermediate said multiplex apparatus and said start-stop distributor comprising a series of electrostatic devices and a pair of sets of storing 40 relays for providing a complete overlap between the selections received by the start-stop distributor and those transmitted by the synchronous multiplex apparatus, means controlled by said start-stop distributor for transferring the effects of impulses stored in said condensers to one set of said storing relays, and means operated subsequent to the transferring of the effects from said condensers to said storing relays for causing the energization of the second set of storing relays depending upon the energized ones of the first set of storing relays.

In witness whereof, I hereunto subscribe my name this 30th day of January A. D., 1922.

MARK B. KERR.
